UNITED STATES PATENT OFFICE

JOSEPH L. HOFFMAN, OF PORTLAND, OREGON.

STEAM-GENERATING PLANT.

1,246,428.

Specification of Letters Patent. Patented Nov. 13, 1917.

Application filed December 10, 1914. Serial No. 876,419.

To all whom it may concern:

Be it known that I, JOSEPH L. HOFFMAN, a citizen of the United States, residing in the city of Portland, county of Multnomah, and State of Oregon, have invented certain new and useful Improvements in Steam-Generating Plants, of which the following is a specification.

My invention relates to steam generating plants, and more particularly to certain improvements in the construction and arrangement thereof whereby I am able to secure greater efficiency in less time and with less fuel. Among the salient objects of my invention are to provide in combination with a steam generating plant an oil burner extension therefor with the oil burner set therein and discharging into the interior of said structure, said extension being of double construction with oil supply pipe arranged in the wall thereof, and with means for running water through the space in said double wall construction and around said oil pipes therein, thereby providing in combination therewith an auxiliary oil heater and also means for heating water; to provide in a plant of the character referred to a construction where all of the heat is utilized in generating steam, even the heat from the fire, where hard fuel is burned, which usually is wasted in the ash chamber below, it being my idea to use water pipes as the grate, or support, for such fire. Other objects and advantages will be apparent from the following description of one practical embodiment of my invention, taken with the accompanying sheets of drawings, illustrating the same, and in which—

Figure 1 is a vertical sectional view longitudinally of a steam generating plant constructed along the lines of my invention; Fig. 2 is a front elevation thereof; and Fig. 3 is a vertical sectional view thereof taken on line 3—3 of Fig. 1.

Referring now more in detail to the drawings, 1 designates a boiler, which may be of the usual construction, having the fire tubes 2 arranged longitudinally thereof in its lower portion, but having through its opposite sides, one or more openings, as 3—3, and through its end a similar opening, as 4,

adapted to be connected to communicate with the interior of the wall structure at the sides, as 5—5, and the end wall 6, said walls 55 being made of steel and of double construction, as illustrated, whereby to provide therein a water space in open communication with the interior of the boiler 1, through the side and end openings 3—3 60 and 4, in said boiler casing. The side and end walls of said structure are connected crosswise, in both directions, within said structure, by means of pipes 7—7 and 8—8, 65 said pipes being connected into the inner walls, whereby to be in open communication with the water space between said double walls and also forming stays to strengthen said structure. In the outer walls, in register with the ends of the pipes 70 connected into the inner walls, are openings with closures, as 7' and 8', whereby it is possible to get access to each pipe for the purpose of cleaning it, or to repair or replace it with a new one. 75

Suitable openings with doors, as at 9—9, are provided through the double wall structure for affording access to the interior thereof, said doors being hinged at their tops, as indicated, and closing downwardly 80 on to an inclined frame, whereby they will remain closed by gravity, or in case they are forced open by an explosion within the structure, they will automatically close again. I have also provided in the lower 85 part of the double wall structure openings with closures as 10 for affording access to the space in the double wall structure, in case it is desired to clean the same and remove settling in the bottom of said space. 90

In the embodiment of the invention here shown for illustrative purposes, it will be noted that there are three rows of circulating pipes 7—7 crosswise through said structure and four rows of the pipes 8—8 extending lengthwise thereof. The lower row of pipes 7 crosswise within said structure is provided with a covering of fire brick 11, or other suitable material, with openings 11' therein, whereby to form a combustion grate 100 for burning rubbish or other hard fuel, with doors 12—12 opening thereto, and the doors 13—13 open to the space below, as indicated.

The two lower rows of pipes 8—8, extend-

ing lengthwise of the structure, are also provided with suitable fire brick 14 for the greater portion of their length, thereby forming therebetween a combustion chamber 15, with an opening 16 through the front double wall 6 of said structure, substantially as illustrated.

The top row of said pipes 8 extending longitudinally of said structure is also provided from the back end thereof forwardly for the greater portion of its length with a covering of fire brick or other suitable material. This covering for the pipes, it will be noted, constitutes directing floors or partitions whereby the heat and products of combustion are forced to make a circuitous passage upwardly, as indicated by the arrows, to the boiler tubes 2-2, and thence therethrough to the chimney 1^a.

20 Mounted on the front of said structure, over the opening 16 to the combustion chamber 15, is an extension 17, of double wall construction, within the wall space of which is coiled an oil supply pipe 18, which enters 25 at the top side thereof, as indicated at 18^a, and emerges from the lower side thereof, as at 18^b, and extends thence to the oil burner 19 through the end wall of said extension 17. A steam supply pipe 20 connects over the oil 30 pipe as it enters the extension 17, in the usual manner.

I have also provided a water supply pipe 21 leading into the space between the walls of said extension 17, and around said oil 35 pipe coil, with an outlet water pipe 22 from the lower side thereof. The front end of said extension 17 is provided with air inlet openings with a regulating wheel 23, adapted to be turned to control the admission of 40 air through the front end of said extension to the burner. An inner flaring shield 24 is mounted on the inside of said extension, around the burner 19, substantially as indicated. As the oil passes through the coil in 45 the extension 17, it is heated and put in better condition for combustion by the heat from the combustion within the extension 17. This extension 17, providing as it does an auxiliary heating means for the oil, as 50 well as for the water, makes it especially well adapted for marine engines.

I realize that changes can be made in the embodiment of the invention shown here for illustrative purposes without departing 55 from the spirit thereof, and I do not, therefore, limit the invention to the specific form here shown, except as I may be limited by the hereto appended claims.

I claim:

60 1. In a steam generating plant of the character referred to, in combination, walls of double construction to provide water spaces therein, water pipes arranged crosswise within said structure and communicat-

ing with the water spaces in said walls, a boiler mounted in the upper part of said structure and in communication with said wall water chambers, whereby water can circulate through said pipes, said walls and said boiler, some of said water pipes being 65 covered with fire brick, or the like, whereby to form two combustion chambers one above the other and communicating with each other in the rear of the structure, an oil burner extension mounted on said structure 70 and opening into the upper combustion chamber, an oil supply pipe arranged in the wall of said extension, and an oil burner set within said extension and connected to said oil supply pipe, substantially as described. 80

2. In combination with a steam generating plant having a housing, a steam boiler and a combustion chamber, an oil burner extension from said housing in alinement with said combustion chamber and having 85 double walls, whereby to provide a space between the walls of said extension, and means for passing water through said space in said double walls of said oil burner extension, substantially as described. 90

3. In combination with a steam generating plant having a housing, a steam boiler, and a combustion chamber, an oil burner extension from said housing in alinement with said combustion chamber and having double 95 walls, an oil supply pipe coiled in the space between said double walls, and an oil burner mounted in said extension and connected to said oil supply pipe, whereby said oil pipe coil is heated from the combustion in said 100 extension, substantially as shown.

4. In a steam generating plant, a metal housing having double walls with water chamber therein, water pipes arranged interiorly thereof and connected into said 105 walls in communication with the water chamber therein, a boiler having its interior connected in communication with said wall water chamber, an oil burner extension opening into said housing and having double 110 walls, an oil pipe arranged in said double wall, a burner in said extension and connected with said oil pipe, and means for running water through the space in said double wall of said extension, whereby to 115 heat the same, substantially as described.

5. In a steam generating plant of the character referred to, in combination, end and side walls of double construction to provide a continuous water chamber therein, 120 pipes arranged in layers, crosswise of each other and connected at their ends into said walls, whereby water can circulate from said walls through said pipes, a boiler mounted in the upper part of said structure and in 125 communication with said wall water chamber, a portion of said boiler extending down into said structure and having the usual fire

tubes therethrough, combination protectors and directing floors on some of said pipes, an oil burner extension mounted on said structure and opening thereto, an oil supply pipe arranged in the wall of said extension, an oil burner set within said extension and connected to said oil supply pipe, and means for running water through the wall

space of said extension, and around said oil pipe therein, substantially as described.

Signed at Portland, Oregon, this 4th day of December, 1914.

JOSEPH L. HOFFMAN.
